UNITED STATES PATENT OFFICE.

MANUEL CARRANZA, OF HAVANA, CUBA.

DESIGN FOR A FAN.

SPECIFICATION forming part of Design No. 22,072, dated December 20, 1892.

Application filed September 9, 1892. Serial No. 445,459. Term of patent 3½ years.

To all whom it may concern:

Be it known that I, MANUEL CARRANZA, of Havana, Cuba, have invented a new and original Design for Fans, of which the following is 5 a full, clear, and exact description.

The drawing represents in plan view a fan decorated in accordance with my design.

The design consists of the representation of

a marine vessel—a caravel—and an expanse of water applied to the ribs of a fan as shown. 10

What I claim is—

The design for a fan as shown and described.

MANUEL CARRANZA.
